UNITED STATES PATENT OFFICE.

RICHARD L. WADE, OF ABERDEEN, WASHINGTON, ASSIGNOR OF TEN PER CENT TO
A. R. A. JOLLY AND TWENTY PER CENT TO W. A. ACKERMAN, BOTH OF ABER-
DEEN, WASHINGTON.

NAIL STRIPPER.

Application filed March 3, 1924. Serial No. 696,717.

To all whom it may concern:

Be it known that I, RICHARD L. WADE, a citizen of the United States, residing at Aberdeen, in the county of Grays Harbor and State of Washington, have invented certain new and useful Improvements in a Nail Stripper, of which the following is a specification.

My invention relates to carpenters' appliances and in particular to nail strippers adapted for use by persons engaged in laying shingles and general roofing work.

The objects of the invention are to provide a portable nail stripper adapted to be worn by carpenters and the like, so constructed and arranged as to be carried at all times in a convenient and accessible position; to provide a nail stripper having means for automatically feeding nails to delivery position; to provide a nail stripper having means for adjustably regulating a delivery portion of said stripper to different sized nails; and to provide a nail stripper equipped with means for preventing accidental dislodgment or displacement of nails carried therein.

With these general objects in view, and such others as will be apparent from the description, the invention resides in the novel combination, construction and arrangement of parts hereinafter described and claimed and illustrated in the accompanying drawings, in which—

Figure 1 is a side elevation of a stripper constructed in accordance with the invention;

Fig. 2, a top plan view thereof;

Fig. 3, a bottom plan view;

Fig. 4, a vertical section on line 4—4 of

Fig. 3;

Fig. 5, a similar section on line 5—5 of Fig. 3;

Fig. 6, a detail section of the delivery end of the stripper;

Fig. 7, a perspective of one of the feed fingers employed; and

Fig. 8, a perspective of another of the feed fingers employed.

In detail, the stripper comprises a member roughly formed in the shape of a shoe and consists of side walls made of leather or other suitable flexible fabric 1 and 2, and end walls 3 and 4. In the preferred form of the invention, each of the side and end walls are constructed of a single strip of

fabric or leather joined along the rear end of wall 4. The bottom of the pocket is formed of a plurality of longitudinally disposed fingers, preferably four in number, designated as 5, 6, 7 and 8. These fingers are disposed in parallel relation and are spaced apart a desired distance to accommodate the size of nails employed by means of shims 18 disposed between the fingers adjacent the rear end of the stripper, as best shown in Figures 2 and 3.

Each of the fingers 5, 6, 7 and 8 is provided adjacent its rear end with one or more depending flanges 9 transversely apertured to receive bolts 10 passed therethrough carrying nuts 11 for clamping the fingers and shims together to provide a unitary bottom for the pocket. The two central feed fingers 6 and 7 are identical in construction and are clearly illustrated in Figure 7. Adjacent the rear end each finger is provided with a flat upper surface 12 and an upstanding rear flange 13. From the forward end of the flat surface 12 the body of the finger is curved toward its outermost end, to provide a dished effect for the bottom when the fingers are assembled in position. The outer ends of each finger are curved slightly upward to extend above the plane of the flat surfaces at the opposite ends of each finger. The finger 5 at one side of the stripper is substantially identical in construction with the intermediate fingers 6 and 7 just described with the exception that it is provided with an upstanding flange 14 along the outer side and across each end thereof. The opposite side finger, designated as 8, is curved along its outer side edge to conform approximately to the outline of the body of the person using the stripper. Along this outer edge and across each end this finger carries an upstanding flange 15 and the fabric or leather strip comprising the sides and end walls of the stripper is secured along its lower end by suitable fastening elements to the respective flanges 13, 14 and 15 of the fingers.

At the delivery end of the stripper the fingers terminate in the same plane and are covered by a depending flange 16 formed on the end wall 3 of the stripper, as best illustrated in Figure 1.

A partition member 17 extends transversely across the stripper between the side walls 1 and 2 and is mounted on a bar 20

extending therebetween and fastened in the side walls, whereby the partition member may be rocked on the bar 20 as a pivot. This partition member is located at the forward end of the flat portions 12 of the feed fingers and serves in effect to form a compartment at the rear of the stripper for the reception of the nails to be employed. From the partition to the delivery end of the stripper the feed fingers are, as previously explained, dished and are formed concave in cross section, as best illustrated in Figure 5, to provide for a ready delivery of the nail shanks into the longitudinal spaces between the fingers along the bottom of the stripper. This concave formation of the fingers provides grooves along the under face of the stripper allowing for ready application of the fingers of the user in drawing the nails from the stripper. The pocket is carried across the chest of the user by means of body straps 19 arranged in any desired manner so as to support the stripper in the most convenient position.

In operation, the stripper is adjusted in position across the chest of the user, and by reason of the configuration of the one side 2 it will lie firmly in position. The nails to be used are then poured into the compartment at the rear end of the stripper from which they will be fed down into the dished portion of the bottom of the stripper underneath the partition 17. By reason of the concave cross sectional configuration of the feed fingers, the shanks of the nails will be guided into the spaces between the fingers and the nails will hang down from the stripper in the position illustrated in Figures 1 and 5. By applying the fingers to the bottom of the stripper the shanks of the nails may be grasped and drawn towards the delivery end of the stripper, from which they may be taken from beneath the flap 16. The upward curvature of the delivery end of the stripper and the depending flap 16 will prevent any accidental displacement of the nails from within the stripper.

While I have illustrated and described certain details and materials entering into the construction and operation of the invention, I desire it to be understood that I do not intend to limit the invention to such as are disclosed, but that any changes and modifications may be made therein as will fall within the scope of the invention as claimed.

I claim:

1. A portable nail stripper comprising a receptacle having a slotted bottom formed of a plurality of longitudinally disposed fingers, and spacing members removably positioned in certain portions of said slots to permit the width of the slots to be varied.

2. A portable nail stripper comprising a

receptacle having a bottom formed of a plurality of longitudinally disposed fingers, 65 spacing members interposed between sections of adjacent portions of said fingers in transverse alignment, and removable fastening means for clamping said fingers and spacing members in assembled position. 70

3. A portable nail stripper comprising a receptacle including a substantially flat rigid bottom formed of a plurality of longitudinally disposed laterally spaced fingers, means for permitting the space between the fingers to be varied which increases or decreases the lateral width of the bottom, and the side and end walls of said receptacle being formed of a single piece of flexible material secured to the edge of said bottom 80 whereby variation of lateral width of said bottom is permitted.

4. A portable nail stripper comprising a receptacle having closed side walls, a bottom for said receptacle, consisting of a plurality of transversely spaced longitudinally disposed members, one end of said receptacle being open to provide a delivery end therefor, spacing members adapted to be disposed between said first named members for regulating the width of the spaces therebetween, means for clamping said first named members and spacing members in assembled relation, and means in said receptacle for causing the shanks of nails to move downwardly into the spaces between said first named members. 90

5. A portable nail stripper comprising a nail holding receptacle, a plurality of transversely spaced longitudinally disposed fingers disposed on the bottom of said receptacle, certain of said fingers terminating short of one end wall to provide a delivery end for said receptacle, means for spacing said fingers, means for clamping said fingers in assembled relation, said fingers being curved upwardly toward the delivery end of said receptacle to prevent accidental dislodgment of nails from within the receptacle, a partition member in said receptacle, and means for supporting said receptacle on the body of the user. 105

6. A portable nail stripper comprising a receptacle having closed side and end walls, a slotted bottom formed of a plurality of longitudinally extending laterally spaced fingers, spacing members positioned between said fingers at one end of the bottom and forming a closed end therefor, and a transverse partition in said receptacle disposed 115 over the slots adjacent the closed end of the bottom to cause the shanks of the nails in said closed end to enter the slots. 120

In testimony whereof I affix my signature.

RICHARD L. WADE.
